(57) **CLAIM**

I claim the ornamental design for an electrical terminal, as shown and described.

DESCRIPTION

FIG. 1 is a front perspective view showing the new design.

FIG. 2 is a top view of the new design.

FIG. 3 is a bottom view of the new design.

FIG. 4 is a right side view of the new design.

FIG. 5 is a left side view of the new design.

FIG. 6 is a front view of the new design; and,

FIG. 7 is a rear view of the new design.

The shading lines shown in the drawings represent the approximate three-dimensional contour of the design, and are not intended to indicate surface decoration.
